LIQUID STORAGE AND DISTRIBUTION
SYSTEM

William von Phul, Jr., New York, N. Y.

Application October 23, 1940, Serial No. 362,405

11 Claims. (Cl. 137—78)

This invention relates to systems for storing and distributing liquids, and relates more particularly to systems by means of which gasoline, fuel oil or other liquids of inflammable nature or of importance to national defense can be stored and distributed with a minimum of danger of destruction or loss by bombing, shell fire and sabotage.

Gasoline and fuel oil normally are stored in large tanks, either above ground in tank farms, or below the ground, for example, in fortified or defense areas. The tank farms are particularly susceptible to damage or destruction by means of bombs or shell fire, for the reason that the tanks are usually closely spaced and an explosion of one tank may set fire to the whole group of tanks on the farm. Moreover, inasmuch as the tanks are above ground, they cast shadows and, even though expertly camouflaged, may be detected readily from the air.

There is less danger of destruction of a group of tanks by a direct hit or an explosion in one of the tanks when they are buried in the ground. Nevertheless, the loss of even one tank, which may hold many thousands of gallons of gasoline or fuel oil may constitute a serious loss and render the area untenable during the ensuing conflagration. In addition to this disadvantage of underground storage systems, considerable difficulty is always encountered in installing such systems and sometimes the terrain is such that it is almost impossible to properly protect the tanks. For example, in order to protect a large vertical cylindrical tank, the excavation must be deeper than the height of the tank, so that a layer of earth or concrete may be placed over the top of the tank to a depth sufficient to afford at least partial protection to the tank. In territory where a rock formation is covered only by a relatively thin layer of earth, such excavations can be made only by blasting and at great expense.

An object of the present invention is to provide a system which is not easily damaged by bombing or shell fire, for storing gasoline and fuel oil or other liquid, and which, even if damaged minimizes the loss of such liquids.

Another object of the invention is to provide liquid storage and distribution systems which are easily installed in substantially any type of terrain, without rendering them visible from the air and which may be located in the most desirable positions for convenient use.

Another object is to provide methods of installing such storage and distribution systems.

Other objects of the invention will become apparent from the description of typical forms of systems embodying the present invention.

In accordance with the present invention, systems for storing and distributing fluids, such as, for example, gas, gasoline, fuel oil and water, are provided which include a network of storage pipes that are used both for the storage and conduction of fluids and disposed in spaced apart relation in a series of filled or covered trenches at such intervals as to minimize the damage caused by the explosion of bombs or shells. The storage pipes are arranged to prevent damage to more than one or two sections thereof by a single explosion, and to prevent the liquid in the remainder of the system from leaking out and being lost when one or more sections are destroyed.

The storage pipes preferably are of sufficient length and diameter to hold relatively large quantities of liquid, as compared with ordinary liquid distribution pipes but are smaller than the usual gasoline or oil storage tanks. They may be connected by means of pipes of smaller diameter which are provided with valves or other checking means for isolating each of the larger storage pipes. In this way, if one section of the network is damaged, only the liquid in the damaged section of the storage pipe will be lost. Inasmuch as numerous pipe sections are used in the system, each section holding only a small fraction of the quantity of liquid normally receivable in the usual gasoline storage tank, for example, of the type used on tank farms, a very large number of sections must be destroyed or damaged before the amount of liquid that is lost will equal the loss caused by destruction of one of these large tanks. Moreover, because of the spacing of the pipe sections and their disposition underground it is possible for a shell or a bomb to explode in the storage area without damaging even one pipe section.

The systems embodying the present invention have the additional advantages of being easy to fill and drain and easy to install underground with a relatively small amount of excavation, as compared with the installation of a series of large storage tanks of equal capacity.

For a better understanding of the present invention, reference may be had to the accompanying drawings in which:

Fig. 1 illustrates a typical layout of a liquid storage and distribution system embodying the present invention;

Fig. 2 is a view in section taken on line 2—2 of Fig. 1;

Fig. 3 is a view of a portion of the system showing details of the connections in the system;

Fig. 4 is a view of a portion of the system illustrating a modified form of valve construction;

Fig. 5 is a view of a form of device for checking the flow of liquid in the system;

Fig. 6 is a view in section of a typical system including the form of flow checking device disclosed in Fig. 5;

Fig. 7 is a side view of another form of flow checking device; and

Fig. 8 is a modified form of liquid storage and distributing system embodying the present invention, as installed in connection with an airplane landing field.

The embodiment of the invention illustrated in Figs. 1 and 2 consists essentially of a plurality of rows 10a, 10b, 10c and 10d of storage pipes 10 which are buried beneath the surface of the earth. As shown in Figs. 1 and 2, each row of pipe sections may be made up of three sections of storage pipe 10 connected in series by means of smaller pipes 11, although a greater or lesser number of pipe sections may be used, as desired. While the pipe sections 10 may have continuous walls, they may be provided with manholes to facilitate cleaning and repair, if desired.

Each of the connecting pipes 11 has a valve 12 therein adjacent to each end of each pipe section 10 so that the pipe sections 10 may be isolated from each other when the valves 12 are closed or placed in communication with each other when the valves are open. The end pipe sections 10 at the upper ends of each row 10a, 10b, 10c and 10d, as viewed in Fig. 1, are connected to the transverse pipe 13 by means of pipes 15. The pipe 13 is provided with a branch 13a through which the liquid may be passed for distribution to the several rows of pipes 10a to 10d. Each of these rows of pipes may be connected to or isolated from the feed pipe 13 by means of valves 16 in the pipes 15. The pipe 13 is also provided with valves 17 between the rows of pipe sections 10a to 10d and the branch 13a. Likewise, the pipe section 10 at the lower end of each row of pipes 10a to 10d, as viewed in Fig. 1, is connected to an outlet pipe 18 by means of pipes 19 which are provided with valves 20. The pipe has an outlet branch 18a and valves 21 are interposed in pipe 18 between the rows 10a to 10d and the outlet branch 18a.

As illustrated in Fig. 3, the liquid distribution pipes 11 are connected near the bottoms of the pipe sections 10 so that the liquid can be substantially completely withdrawn from the pipe sections. Preferably the pipes 11 are made up of sections 11a having flanged ends 11b which permit ready replacement of damaged sections of these pipes and the valves 12. The other distribution pipes and valves may be arranged similarly.

The rows of storage pipes 10 and the interconnecting liquid distribution pipes 11, 13, 15, 18 and 19 may be readily installed in trenches which may be dug by means of a ditch digging machine. The individual tanks and the connecting pipes are covered, for example, with dirt after they have been positioned in the trenches. Inasmuch as it is possible to dig a trench very rapidly with a ditch digging machine, the time and labor required for installing a typical system is greatly reduced, as compared with the time and labor required to install one or more large cylindrical storage tanks.

In installing the system, the individual stor-

age pipes 10 should be spaced at such intervals that a direct bomb or shell hit on one of the pipes 10 will not damage or rupture the pipes 10 on opposite sides thereof. In this way, more than one pipe would be ruptured or destroyed and the contents thereof lost, only when a connecting pipe 11 and the isolating valves 12 are destroyed or ruptured. Even under these circumstances the contents of only two sections would be lost.

As indicated in Figs. 2 and 3 the valves 12, as well as the other valves, may be actuated by means of actuating handles 22 fixed to elongated shafts 23 connecting with the valve plugs or gates; the valve actuating handles 22 being disposed in boxes or manholes 24 at the surface of the earth where they are readily accessible, as shown in Fig. 2 or above ground as shown in Fig. 3. If desired, electrically actuated valves 25, shown in Fig. 4, may be used, these valves being controlled from a central control panel.

With this system in operation, it will be seen that by isolating the various tanks, only a relatively small number thereof may be damaged by a single direct hit, and this damage cannot spread to other tanks which are isolated therefrom. However, by opening the various valves 12, 17 and 16, it is possible to fill the entire system and by opening the valves 12, 20 and 21, it is possible to drain the entire system.

If desired, in order to facilitate draining of the various storage pipes 10, when one or more of the pipes 10 are damaged, additional by-pass pipes 25 may be connected to the distribution pipes 11 between the valves 12 of the rows 10a to 10d so that the liquid may be by-passed around damaged sections. Moreover, other by-pass pipes may be connected at different points in the system, for example, a pipe 26 may extend substantially parallel to the rows 10a to 10d and is connected to the pipes 13, 25 and 18. As many of the pipes 26 may be used in the system, as may be desired.

It will be understood that the by-pass pipes 25 and 26 may be provided with valves 27 similar to valves 12, so that communication between the parallel rows of pipes may be shut off.

As illustrated in Figs. 5, 6 and 7, another type of liquid checking device may be substituted for one or more of the valves 12, 16, 17, 20, 21 and 27, when the system is drained by means of pressure exerted on the fluid. For example, one or more motor driven compressors may supply carbon dioxide under pressure to the system from a gas tank B to blow the liquid from the system, as shown in Fig. 6.

The checking device disclosed in Fig. 5 consists of a plurality of straight sections of pipe 11c, 11d, 11e, 11f and 11g connected by 90° bend elbows 11h to form an inverted U-member 29 of greater height than the pipe section 10. The pipe 11e is provided with a check valve 30 which permits air to leak into the U-member 29 when the liquid is not being forced therethrough, thereby permitting the liquid to drop in pipes 11d and 11f to the level of the liquid in the pipe sections 10. When liquid is forced upwardly along the pipes 11d or 11f the air escapes through the valve 30 and the liquid flows over the U-member 29 into the next adjacent pipe section 10. With this construction, when a U-member 29 is broken the liquid can leak from, at most, only two sections 10, the air lock on opposite sides of these sections preventing other sections from being drained. By forming the U-members 29 of a series of sections of pipe, it

is easy to by-pass from one section of the U-member 29 to another section of another U-member 29 and thereby to cut one or more damaged pipe sections 10 out of the system.

The form of checking device disclosed in Fig. 7 is similar in principle to the device disclosed in Fig. 5, in that it includes a U-member 35 of greater height than the pipe sections 10. The U-member 35 is formed of two generally S-shaped, flanged pipes 35a and 35b which may be formed of a series of straight and elbow pipes. The S-shaped pipe 35b may be provided with an air escape valve 36 of the type described above.

As illustrated in Fig. 8, a similar arrangement may be provided outside of an area which is to be used, for example, as an airplane landing field. In this system, main storage tanks 40 and 41 of relatively large capacity may be disposed at the edge of the landing field area L, either above or below ground, to receive the main supply of gasoline or fuel oil. The large tanks 40 and 41 may be connected to a pipe 42 by means of short pipes 43 and 44 each having a valve 45 therein. A similar valve 45 is disposed in the pipe 42 between the tanks 40 and 41. Opposite ends of the pipe 42 are connected to the storage pipe sections 46 and these pipe sections 46 are connected by small liquid distribution pipes 47. Suitable valves 48 are interposed in the pipes 47 and 42 adjacent the ends of the various sections 46. The large tanks 40 and 41 serve as the main liquid supply from which liquid is withdrawn as desired. Should the large tanks 40 and 41 be damaged by bombing or shell fire, a reserve supply of liquid is available in the storage pipe sections which will be sufficient to supply the aircraft at the field until additional storage facilities are made available.

From the foregoing description, it will be apparent that I have provided a simple, readily installed liquid storage and distribution system which prevents the liquids from being lost or destroyed by shell fire, bombing or other explosions. Moreover, these systems localize fires created by the explosion of one or more tanks.

It will be understood, of course, that there may be other arrangements of storage sections or tanks than those described above, due to variations in the type of terrain in which they are installed, and accordingly, the forms of the invention described above should be considered as illustrative and not as limiting the scope of the following claims.

I claim:

1. A system for storing and distributing liquids comprising a plurality of spaced apart storage containers formed of sections of pipe for storing and distributing liquid, each section of pipe being of materially larger cross-sectional area than is required to distribute said liquid but smaller in cross-sectional area than the usual storage tank, pipes of little storage capacity and small cross-sectional area connecting said storage containers, checking means in each pipe of little storage capacity for isolating the liquid in said containers, and means to introduce liquid into said pipes and containers and remove it therefrom.

2. A system for storing, protecting and distributing liquids comprising a plurality of spaced rows of storage containers formed of sections of pipe of materially larger cross-sectional area than ordinary flow conduits, but of materially smaller cross-sectional area and storage capacity than ordinary storage tanks disposed beneath

the surface of the earth, each row containing a plurality of spaced apart storage containers connected in series by liquid distribution pipes of small cross-sectional area and storage capacity having checking means therein for isolating the liquid in said storage containers, and other small liquid distribution pipes connecting said rows in parallel communicating with the storage containers at the ends of said rows for delivering liquid to and withdrawing liquid from said storage containers.

3. A system for storing, distributing and protecting liquids comprising a plurality of rows of storage containers spaced at such intervals as to localize damage to said containers by explosions, each container being formed of a section of pipe of materially larger cross-sectional area than ordinary flow conduits, but of materially smaller cross-sectional area and capacity than ordinary storage tanks each row including a plurality of said storage containers connected in series by liquid distribution pipes of small cross-sectional area and capacity, checking means in said distribution pipes interposed between said storage containers for isolating the liquid in said storage containers, a filling pipe connecting the storage containers at one end of said rows, for distributing liquid to all of said storage containers and a draining pipe connecting the storage containers at the other end of said rows, for withdrawing liquid selectively from said rows.

4. A system for storing, distributing and protecting liquids comprising a plurality of rows of storage containers disposed beneath the surface of the earth and spaced at such intervals as to localize damage to said containers by explosions, each container being formed of a section of pipe of materially larger cross-sectional area than ordinary flow conduits, but of materially smaller cross-sectional area and capacity than ordinary storage tanks, each row including a plurality of said storage containers connected in series by liquid distribution pipes of small cross-sectional area and capacity, checking means in said distribution pipes interposed between said storage containers for isolating the liquid in said storage containers, a filling pipe connecting the storage containers at one end of said rows, for distributing liquid to all of said storage containers and a draining pipe connecting the storage containers at the other end of said rows, for withdrawing liquid selectively from said rows.

5. A liquid storage and distribution system comprising a plurality of rows of storage containers, each row including a plurality of storage containers, each container being formed of a section of pipe of materially larger cross-sectional area than ordinary flow conduits, but of materially smaller cross-sectional area and capacity than ordinary storage tanks, said storage containers being disposed underground and spaced apart a sufficient distance to localize damage by explosions, liquid distribution pipes of small cross-sectional area and capacity connecting the interior of each storage container to adjacent storage containers to permit liquid to flow from one storage container to the adjacent storage containers, valves in said distribution pipes for isolating said storage containers from each other and means accessible from the surface of the earth for opening and closing said valves.

6. A liquid storage and distribution system comprising a plurality of rows of storage containers, each row including a plurality of stor-

age containers, each container being formed of a section of pipe of materially larger cross-sectional area than ordinary flow conduits, but of materially smaller cross-sectional area and storage capacity than ordinary storage tanks, said storage containers being spaced apart a sufficient distance to localize damage by explosions, liquid distribution pipes of small cross-sectional area and capacity connecting said storage containers to permit liquid to flow from one storage container to the adjacent storage containers, and vertically disposed substantially U-shaped sections of pipe of greater height than said storage containers forming a part of said liquid distribution pipes for checking flow of liquid from undamaged storage containers to damaged storage containers and distribution pipes.

7. A liquid storage and distribution system comprising a plurality of rows of spaced apart storage containers, each container being formed of a section of pipe of materially larger cross-sectional area than ordinary flow conduits, but of materially smaller cross-sectional area and capacity than ordinary storage tanks, liquid distributing pipes of small cross-sectional area and capacity connecting the storage containers in each row to permit liquid to flow through said distributing pipes from one storage container to another including a pair of communicating substantially U-shaped pipes of greater height than said storage containers adjacent the storage containers, and means for delivering liquid to and withdrawing liquid from said pipes and containers.

8. A liquid storage and distribution system comprising a plurality of rows of spaced apart storage containers, each container being formed of a section of pipe of materially larger cross-sectional area than ordinary flow conduits, but of materially smaller cross-sectional area and capacity than ordinary storage tanks, liquid distributing pipes of small cross-sectional area and capacity connecting the storage containers in each row to permit liquid to flow through said distributing pipes from one storage container to another including a pair of communicating substantially U-shaped pipes of greater height than said storage containers adjacent the storage containers, air inlet valves in the top portions of said U-shaped pipes, and means for delivering liquid to and withdrawing liquid from said pipes and containers.

9. A liquid storage and distribution system comprising a plurality of rows of spaced apart storage containers, each container being formed

of a section of pipe of materially larger cross-sectional area than ordinary flow conduits, but of materially smaller cross-sectional area and capacity than ordinary storage tanks, liquid distribution pipes of small cross-sectional area and capacity connecting the storage containers in each row to permit liquid to flow through said distribution pipes from one storage container to another, a valve in each end of said distribution pipes adjacent to said storage containers for isolating said storage containers and means for delivering liquid to and withdrawing liquid from said pipes and storage containers.

10. A liquid storage and distribution system comprising a plurality of rows of spaced apart storage containers, each container being formed of a section of pipe of materially larger cross-sectional area than ordinary flow conduits, but of materially smaller cross-sectional area and capacity than ordinary storage tanks, liquid distribution pipes of small cross-sectional area and capacity connecting the storage containers in each row to permit liquid to flow through said distribution pipes from one storage container to another, a valve in each end of said distribution pipes adjacent to said storage containers for isolating said storage containers, liquid by-pass pipes of small cross-sectional area and capacity connected to the distribution pipes in said rows at points intermediate said valves, and means for delivering liquid to and withdrawing liquid from said pipes and storage containers.

11. A liquid storage and distribution system comprising a plurality of rows of spaced apart storage containers, each container being formed of a section of pipe of materially larger cross-sectional area than ordinary flow conduits, but of materially smaller cross-sectional area and capacity than ordinary storage tanks, liquid distribution pipes of small cross-sectional area and capacity connecting the storage containers in each row to permit liquid to flow through said distribution pipes from one storage container to another, a valve in each end of said distribution pipes adjacent to said storage containers for isolating said storage containers, liquid by-pass pipes of small cross-sectional area and capacity connected to and communicating with the distribution pipes in said rows at points intermediate said valves, valves in said by-pass pipes between said rows, and means for delivering liquid to and withdrawing liquid from said pipes and containers.

WILLIAM VON PHUL, JR.
